RECORD-CONTROLLED SOUND-REPRODUC-
ING INSTRUMENT

Kurt Emde, Itasca, Ill., assignor to Zenith Radio Corporation, Chicago, Ill., a corporation of Illinois

Application April 30, 1941, Serial No. 391,081

3 Claims. (Cl. 312—8)

The present invention relates to record-controlled sound-reproducing instruments, and more especially to sound recorders and reproducers of the electrical type and radio phonographs employing record supporting and propelling mechanism.

In recording and reproducing instruments of the type used prior to the present invention it has been inconvenient to obtain access to the means which operatively support the record or records. The cabinet, or other housing, which usually encloses reproducing or combined recording and reproducing apparatus is generally provided with a lid which must be raised to obtain access to the record supporting mechanism. In lieu of housing such mechanism adjacent the top of the cabinet and obtaining access to it by raising a lid or other cover which is usually a repository for miscellaneous articles, it has been proposed to house it in a drawer which can be partially withdrawn from the cabinet. This last named arrangement has obvious disadvantages, among which are increased costs of the cabinet structure, inaccessibility of certain of the parts, unless the drawer is at least as long as the depth of the housing, and a fixed level of the drawer when it is withdrawn to afford access to the record supporting mechanism. Also a swinging shelf support has been proposed in which swinging movement is obtained by hinging a portion of one wall of the cabinet. The disadvantages of this arrangement are obvious if the portion of the cabinet wall selected to be hinged is one which contains the loud speaker. Inasmuch as the loud speaker must, for best tone quality, be mounted upon a surface of relatively large area and the hinged portion of the wall of the cabinet must be relatively long to bring the record supporting mechanism to an accessible point, the section of the wall containing the speaker is the only portion readily available for hinging. If an upper portion of the cabinet is selected to be hinged, the radio receiver must then be placed in an awkward position within the cabinet so that its controls are relatively inaccessible. This invention has for its aim to eliminate all of the disadvantages inherent in means known to the prior art for obtaining access to a record playing or recording mechanism. This aim is accomplished by providing a swingable motor board which is mounted in a novel manner in the housing or cabinet enclosing the apparatus and for which a novel operating means is provided.

The primary object of the present invention, therefore, is to provide, in a recording and re-

producing instrument, or a radio-phonograph, novel means for obtaining ready and convenient access to the record supporting mechanism.

Another object of the present invention is to provide movable means of novel form for bringing a record supporting mechanism into a convenient position for loading and unloading.

Still another object of the invention is to provide a radio-phonograph combination in which all of the component parts thereof are arranged for convenient operation with substantially no decrease in the operating efficiency of any one of these components.

A still further object of the present invention is to provide a device for a record supporting mechanism, whereby said mechanism may be moved from an enclosure to an elevated position outside of the enclosure.

A still further object of the present invention is to provide a device for a record supporting mechanism, whereby said mechanism may be moved to an elevated position by resilient means, for affording convenient access to the mechanism.

A still further object of the present invention is to provide a device for a record supporting mechanism whereby said mechanism may be moved to a convenient position under control of novel control means.

A still further object of the present invention is to provide a device for a record supporting mechanism whereby said mechanism may be moved to a convenient position under control of novel control means operable by the hand or foot of a person desiring access to the record supporting mechanism.

A still further object of the present invention is to provide novel means for checking the movement of a movable member substantially without shock to the parts carried by the movable member.

Still another object of the present invention is to provide a movable record supporting mechanism which is swingable from one level to a more accessible level with respect to the top of the enclosure housing the apparatus.

A still further object of the present invention is to provide a combined radio-phonograph instrument of the "chair side" type housed in a cabinet in which the controls of the radio-set and the record playing mechanism are accessible to a person seated in a chair placed alongside of the instrument.

A still further object of the present invention is to provide a combined radio-phonograph instrument of the "chair side" type housed in a

cabinet in which the record supporting mechanism is movable in a novel manner to a position outside of the cabinet under control of a person seated in a chair placed alongside of the instrument.

A still further object of the present invention is to provide a combined radio-phonograph instrument of the "chair side" type in which a novel device is provided for moving a record supporting mechanism into and from positions within and out of the cabinet of said instrument, movement of this device being controlled by button means located on top of the cabinet.

Other and more specific objects of the present invention will become apparent as the detailed description of a selected number of illustrative embodiments proceeds with reference to the accompanying drawings in which:

Figure 1 is a perspective view of a combined radio-phonograph embodying the present invention, and

Figure 2 is a vertical longitudinal sectional view of the instrument of Figure 1.

Referring now, to the drawings, the invention is shown installed in the cabinet 91 of an instrument of the "chair side" type. The instrument is particularly adapted to be positioned alongside of a chair, davenport, or other piece of furniture in the manner of an ordinary end table or the like so that the controls 92 of a radio set 93 mounted in the cabinet are conveniently accessible to a person seated in the chair. By the novel means to be described, the record playing device, and recording device if one is provided, are also readily accessible to a person seated in a chair alongside of the instrument. The cabinet also houses a loud speaker 94 and a record supporting mechanism 96. The loud speaker is preferably so mounted that it may be readily moved from one side of the cabinet to the other depending on the location of the chair or other piece of furniture with respect to the instrument. This provides for good tone quality whether the chair is placed on one side or the other of the instrument. The record supporting mechanism 96 comprises the usual turntable 97, driven by the motor 98, and if desired, the record feeding mechanism 99. A pickup device 101 cooperates with the record on the turntable 97, and a recording device may be provided if desired for the purpose of recording sound on a record blank on the turntable 97. The mechanism 96 comprises a motor board 103, and suitable flexible connecting cables 148 and 149 are connected to the motor 98 and the pickup device 101. The motor board 103 and the mechanism 96 carried thereupon are suspended from angle brackets 100 mounted on rails 102 adjacent to the top 104 of the cabinet by a pair of front link members 106 and 107, and a pair of rear link members 108 and 109. The link members 107 and 109, which support one side of the motor board 103, are pivotally connected at 110 and 111 to the bracket 100. The link members 106 and 108 are pivotally connected to a similar bracket 100 carried in a similar manner by the other rail 102. If desired, the radio set may be secured, as shown, to a partition 117 in the cabinet. The remaining ends of link members 107 and 109 are pivoted to the motor board 103 at the points 118 and 119, and the link members 106 and 108 are pivoted to the motor board 103 at the points

121, one of the latter being concealed in Figure 1 of the drawings by the cabinet wall.

Record-supporting mechanism 96 may be retained in either of its two positions by means of springs 123 which act on an arm 126 secured to the link 109. The spring 124 acts on a like arm 126 (not shown) on the link 108. The springs 123 are connected to a rod 129 which extends between and is connected to the arms 126 on the links 108 and 109. The remaining ends of the springs 123 and 124 are connected to projections 132 on the brackets 100. This provides a balanced spring arrangement which exerts equal force on each side of the motor board. A single spring may be used if desired. However, the constructions and arrangement employing two springs is preferred.

Record-supporting mechanism 96 may be moved to its position outside of the cabinet 91 and substantially above the top 104 thereof upon operation of a push button 133. The push button 133 is shown at the preferred location, protruding above the top of the cabinet. The body portion of the push button slides in an aperture 20 in the top 104 of the cabinet 91. The end of the body portion of the push button is positioned to rest against the rod 129. Upon exertion of pressure on the exposed end of the button, the links 108 and 109 are moved in a counter-clockwise direction to move the mechanism 96 forward, or toward the right as viewed in Figure 2 of the drawings. When the springs 123 pass the pivot points of the links 108 and 109, they serve to move the mechanism forwardly and upwardly toward the position outside of the cabinet. In the course of this movement, the links 106 and 107 frictionally engage the buffer springs 136, one of which is shown in the drawings. The buffer springs 136 are both alike, and therefore only one will be described, it being understood that the description applies equally well to the other. The spring 136 is a relatively long, flat, flexible member secured to a side of the cabinet 91 by suitable means such as the screws or bolts 141. A portion between the ends of the spring members 136 is curved outwardly as shown in order to engage the links 106 and 107 with increasing friction as the record-supporting mechanism 96 moves toward its position outside of the cabinet 91. The effect of the curved portion of the arms 136 serves to bring the mechanism to a stop at the end of its travel without disturbing the parts associated therewith. The link members may, if desired, be offset as at 143 between their ends, so that transmission of vibration from the cabinet 91 to the motor board 103, or vice versa, may be thereby minimized.

60 The cabinet is closed by a panel 145 secured to the motor board 103. The end of the cabinet may be provided with a panel or door 146 hinged at 140 which carries an open ended box 147, designed to hold records.

65 In operation of the device, the mechanism 96 may be supplied with a record or records when it is in its elevated position outside of the cabinet. When it is desired to obtain access to the mechanism 96, the push button 133 is depressed, thereby moving the motor board against the force of the springs 123. As the springs pass the point of pivotal connection of the links to the brackets, their action on the motor board 103 will be reversed so that they will propel it forwardly to its position outside of the cabinet.

Movement of the motor board while it is being propelled by the springs 123 is gradually retarded by the springs 136 as the links 106 and 107 force the springs to assume a flat configuration between their ends. The force exerted by the springs 123 and the retarding action of the buffer spring members 136 are so proportioned that the motor board 103 with the record-supporting mechanism 96 comes to rest at a definite and desired point. The mechanism may be conveniently returned to its position inside of the cabinet 91 by moving it against the force of the springs 123 until the springs pass the point of pivotal connection of the links, whereupon the springs will act to move the motor board to its position inside of the cabinet 91. It is to be noted that the mechanism 96 will operate in a normal manner in either position of the motor board 103 and that this mechanism may be of any desired type and need not be specially designed for use with the supporting arrangement of this invention.

While the invention has been described and explained in detail in connection with a preferred embodiment thereof, it is to be understood that the invention may be embodied in other forms and, therefore, the invention is not limited except as indicated by the terms and scope of the appended claims.

The invention claimed is:

1. The combination, in a supporting table having a swinging support arranged to swing said table into and out of an enclosure, of means associated with the swinging support for said table for resiliently forcing said table into said enclosure on one side of an overcenter point and toward an extreme position out of said enclosure on the other side of said overcenter point, and manually operable means for forcing the first said means past said overcenter point to a position in which the first said means operates to force said table toward said extreme position out of said enclosure.

2. The combination, with a casing and a supporting table having swinging supports pivoted thereto and to said casing and arranged to swing said table into and out of said casing, of means associated with the swinging supports for said table acting to influence the movement of said table into said casing on one side of an overcenter point and toward an extreme position out of said casing on the other side of said overcenter point, and a manually operable plunger extending through a wall of said casing acting upon operation to move the swinging supports for said table against the influence of said means and thereby move said table from its position within said casing and to force said means past said overcenter point whereupon the influence of said means upon said table is to move it toward its extreme position out of said casing.
3. The combination, with a casing and a supporting table having swinging supports pivoted thereto and to said casing and arranged to swing said table into and out of said casing, of means attached to the swinging supports for said table and movable with the movement thereof past an overcenter point constituted by the pivotal attachment of said swinging supports to said casing, said means acting to influence said table into said casing on one side of said overcenter point and toward an extreme position out of said casing on the other side of said overcenter point, and a manually operable plunger extending through a wall of said casing acting upon operation to move the swinging supports for said table against the influence of said means and thereby move said table from its position within said casing and to force said means past said overcenter point whereupon the influence of said means upon said table is to move it toward its extreme position out of said casing.
